UNITED STATES PATENT OFFICE.

OWEN D. KINSEY, OF WAUWATOSA, WISCONSIN.

GRINDER.

Application filed May 24, 1926. Serial No. 111,158.

My invention relates to a power operated grinder for grinding, leveling or smoothing down metallic surfaces, as for example the worn surfaces of locomotive frame jaws, main and side rod ends; brass fits; valve gear repair, and numerous similar operations which heretofore have been performed with manually operated files entailing tiresome physical labor and a loss of considerable time.

10 My invention has for its object the provision of a device of the character herein described which may be easily handled and whereby worn down surfaces—in fact any metal surface—may be rapidly leveled and 15 the saving of both time and files obtained.

The objects and advantages of my improved grinder will be readily comprehended from the following detailed description of the accompanying drawings, wherein:—

20 Figure 1 illustrates my improved grinder in elevation.

Figure 2 is a longitudinal sectional view of my improved grinder, with an intermediate portion broken away.

25 Figure 3 is a longitudinal sectional view of a portion of the main cylinder, namely the motor containing and air admitting port portions thereof.

Figure 4 is a cross sectional view taken on the line 4—4 of Figure 2.

Figure 5 illustrates a modified form, in elevation, merely the grinding wheel end and a portion of the motor containing cylinder being shown.

30 Figure 6 is a longitudinal sectional view of the same on a somewhat enlarged scale.

Figure 7 is a perspective view of the bearing housing or plug at the inner or valve end of the device.

My invention relates to a grinder especially adapted for leveling down the worn surfaces of locomotive frame jaws and in the construction shown in Figures 1 to 4, it comprises a main cylinder or outer casing 10 which constitutes a housing for a rotary type of air motor or air rotor indicated generally at 11. The air motor is provided with a spindle 12 of predetermined length for the purpose of receiving a grinding wheel 13 secured to the spindle so as to rotate therewith.

The cylinder 10 on one side and beyond the mounting of the air motor 11 is segmentally cut away as indicated at 14, see Figure 1, in order to provide a proper opening commensurate with the size of and to accommodate the 55 grinding wheel 13 in order that the latter may be accessible and be applied to the material or surface on which the grinder is to operate.

The cylindrical housing 10 is formed to provide or afford a true alignment for the three 60 radial ball-bearing mountings 15, 16 and 17 whereby the air motor is maintained in proper position and its free rotation permitted.

The air rotor is also provided with a trunnion 18 which receives a thrust collar 19, 65 about which the ball-bearing 17 is mounted; and this end of the cylinder 10 is provided with a plug or bearing housing 20; the cylindrical housing 10 and the bearing housing 20 being shown apertured and provided with a 70 suitable grease plug as at 21 which communicates with the spacing intermediate of the thrust collar 19 and the ball-bearing mounting 17, as clearly shown in Figure 2, thus enabling proper lubrication of the bearings at 75 this inner end of the motor or air rotor. The inner end of the spindle 12 is also provided with a thrust collar 22 substantially similar to the thrust collar 19; the thrust collar 22 being disposed intermediate of the ball-bearing 80 mounting 16 and the adjacent end of the air rotor 11. The thrust collars 19 and 22 are intended to rotate or revolve with the air rotor 11 and these thrust collars in turn provide endwise bearings for the blades 23 of the air 85 rotor.

The air motor or rotor 11 is in the nature of a cylinder provided with a plurality of longitudinal slots, as for example three in number as shown at 24 in Figure 4, in each 90 of which is secured or placed a loosely held or radially slidable blade member 23 which is free to move in and out radially through the action of centrifugal force. The cylindrical housing 10, at what may be termed the inner 95 end of the spindle 12, is provided with a bearing housing 25 whereby the thrust collar 22 and the bearings 16 are suitably held in place and which, in conjunction with the bearing housing 20 maintain the rotor or air motor in 100

proper position relative to the inner diameter of the cylindrical housing 10. That is to say, the housings 20 and 25 are so formed that the rotor cylinder or air rotor 11 will be held eccentrically in the main or outer housing 10, as clearly shown in Figure 4, so that the blades of the rotor are caused to follow an eccentric circle, in other words made to move inwardly and outwardly.

- 10 As shown in Figure 4, the turbine type of air motor or rotor 11 is mounted in the main cylinder or housing 10 with one side in snug relation with the wall of the outer cylinder 10. The portion of the main cylinder or housing 10 in which the rotor is mounted is provided with a muffler 26, which is provided with a plurality of air escape ports 27 arranged at a predetermined point relative to or prearranged distance from the outlet ports 26^a of the main cylinder or housing 10 so that the exhaust air passing through the ports 26^a will be caused to encircle or flow about the main housing or cylinder 10 within the muffler 26 before the air is exhausted from the muffler through the exhaust ports 27 therein. As a result a current of air is made to flow about the main housing 10 and constitutes a cooling medium.

One end of the main housing 10 is provided 30 with a valve housing 28 shown threaded onto the end of the main housing or cylinder 10. The valve housing 28 is shown provided with a cone shaped valve 29 provided with the air inlet tube or stem 30, the outer end whereof is 35 shown provided with a suitable union as at 31 for attachment to an air line leading to a suitable source or supply of compressed air. The valve housing 28 is provided with air ducts 32 with which ports 33 in the valve 29 40 are adapted to register upon proper rotation of the valve 29 induced by rotation or turning of handle 34 which is rotatably mounted and held in place by sleeve 35 and the union 31; extent of rotation of the handle 34 being determined by a suitable stop pin shown at 36 secured in the valve housing 28 and extending into the circumferential slot 37 of the sleeve 35. In order to maintain a proper positioning of the cone shaped valve 29 relative to the 50 ports and air ducts, I show the base of the valve chambered to receive a suitable compression spring as at 38 which at one end bears against the bearing housing 20 as shown in Figure 2; the spring maintaining a proper 55 tension on the valve and therefore inducing the valve to keep its seat as is clearly apparent from the construction.

The outer end of the spindle 12 is provided 60 with an end bearing housing 39 suitably secured to the outer end of the main housing or cylinder 10, as for example by the screws 40. The housing 39 is eccentrically bored, in keeping with the housing members 20 and 25 so as to receive the outer end of the spindle 12 and 65 thus maintain the air motor or rotor 11 in its

eccentric relation with the outer cylinder or housing 10. The housing 39 is formed to receive the ball bearing mounting 15 previously referred to and also to receive a felt washer indicated at 41 arranged intermediate 70 of the ball bearing mounting 15 and the inner wall or flanged portion 42 of the housing 39; the ball bearing mounting 15 being maintained in proper position by means of the spindle nut 43 secured to the threaded end of 75 the spindle 12. The outer side of the housing 39 is shown provided with an end grease cap 44 which may be secured in place in any suitable manner, as for example by the screws 45; the grease cap 44 being shown provided with a grease plug as at 46, while the outer end is shown provided with a handle 47 secured to the cap in any suitable manner, as by means of the fillister head screw 48.

The grinding wheel 13 is shown secured on 80 the spindle 12, so as to rotate therewith, by means of the collars 49 and 50, the ends whereof are in abutting relation with the bearing members 16 and 15, respectively, with the result that endwise movement of either 85 the rotor or grinding wheel is absolutely impossible. The inner end of the collar 49 is shown preferably provided with a felt washer 51; the washers 51 and 41 preventing the outflow of the lubricant or grease from the 90 bearing housings 25 and 39 respectively. The bearing housing 25 is shown provided with a grease plug 52 for introducing lubricant into the space intermediate of the thrust collar 22 and the ball-bearing mounting 16. 100

In Figures 5 and 6 I illustrate a modification of my invention which is especially adapted for grinding or smoothing down welded surfaces and the like; the grinder, however, being operated by means of an air 105 rotor identical in every respect with the air rotor disclosed in the previously described construction and which in turn is also mounted eccentrically within the outer casing or cylinder as in the previously described construction. In the modified form shown in Figures 5 and 6, the outer casing or cylinder 53 is shortened so as to terminate with the outer end of the bearing housing 54, which is substantially similar to bearing housing 25 110 and which encloses the thrust collar 22 and the ball-bearing mounting 16 disposed about the spindle 12 of the air rotor 11. The housing 54 is provided with a tapped opening to receive the threaded end of a spindle and bearing housing 55 through which spindle 12 is disposed; the opposite end of the spindle housing 55 being enlarged and provided with the ball-bearings 56, while the spindle 12 is preferably provided with a felt washer 115 as at 57, all of which are maintained in place by means of the shield or wheel cover member 58 which has an externally threaded hub portion 59 which screws into the threaded end of the spindle housing 55. The shield 120

or grinding wheel cover 58 is left open at the opposite side and is cut away segmentally as shown in Figure 5 for the protrusion of the grinding wheel 60 which is secured to the 5 reduced portion of the spindle 12 by means of the collars 61 and the nut which screw onto the end of the spindle; the wheel 60 being made to revolve with the spindle.

The modification of Figures 5 and 6 show 10 the outer casing or main housing formed in sections or of separate pieces instead of the single piece housing shown in Figures 1 and 2 in order to facilitate easy assembly and permit proper access to the various parts.

15 In the operation of my improved device, air is admitted from a suitable source of supply by properly turning handle 34 which in turn rotates the valve 29 and properly aligns its ports 33 with the air admitting ports 32 20 in the valve-housing; the ports 32 terminating in the circumferential portion 32^a, which in turn communicates with the air duct 62 formed in the side wall of the bearing plug or housing 20. The duct 62 is flared some 25 what in one direction (see Figures 4 and 7) so as to establish communication with the air port portion 32^a; the duct 62 being located on one side of the point of contact between rotor 11 and the wall of the cylindrical housing 10, while the exhaust ports 26^a in the housing 10 are located on the opposite side 30 of the point of contact; the rotor revolving in the direction indicated by the arrow in Figure 4.

35 I have shown what I believe to be the simplest adaptations of my invention which has been described in terms employed merely as terms of description and not as terms of limitation as structural modifications may 40 be made without, however, departing from the spirit of my invention.

What I claim is:—

1. In a grinder of the character described, an elongated main housing internally cylindrical and having a cut-away portion at one end, an air rotor in said housing provided with a trunnion on one end and a grinding wheel carrying spindle on the other end, thrust collars secured about the trunnion and 45 said spindle and adapted to rotate with the rotor, antifriction bearing holding housings mounted in the main housing at opposite ends of the rotor and at the outer end of the spindle whereby the rotor is eccentrically mounted in the main housing in contact with one side therewith, an air admitting port disposed transversely of one of said bearing holding housings, exhaust ports in the side wall of the main housing at a point removed 50 from the point of contact between the rotor and said main housing, an air control valve rotatably secured to one end of the main housing, a grease holding closure cap for the spindle receiving end of the housing, and a muffler secured about the main housing and pro-

vided with discharge ports on the side of the housing opposite to the side provided with said exhaust ports.

2. In a grinder of the character described, comprising a housing internally cylindrical, 70 an air rotor mounted in said housing and provided with a grinding wheel carrying spindle, the rotor being provided with radially disposed slots, blades radially movable in said slots, bearing elements at opposite ends 75 of the rotor whereby the latter is eccentrically mounted in said housing and longitudinal movement of the blades prevented, said elements being arranged to provide lubricant holding chambers at both ends of the rotor, the elements at one end being formed with an air admitting duct, an air control valve secured against the last mentioned element and provided with oppositely diverging ports, means for yieldingly forcing said valve 80 in one direction to compensate for wear, and a handle rotatably secured to one end of the housing for controlling said valve.

3. In a grinder of the character described, 90 a cylindrical shell provided with a shield-forming extension, eccentrically bored bearing housings spaced apart longitudinally in the shell against movement, a cylindrical block provided at one end with a trunnion and at the other end with a grinding wheel carrying spindle, the trunnion being journaled in one of said bearing housings while the spindle is journaled in the other bearing housings whereby the cylindrical block 95 is eccentrically held in said shell in close relation therewith at one side of the shell, said block having radial slots extending lengthwise thereof, blade members loosely slideable in said slots, one of said bearing housings having a cut-away portion in its cylindrical 100 side to provide an air duct, the cylindrical shell having ports therethrough at a point removed from the point of contact between the shell and said cylindrical block, an air controlling valve rotatably secured at one 110 end of the shell and adapted to effect communication with said air duct in the bearing housing, said valve having a tubular extension, a handle secured about said extension for rotating said valve, and a muffler shell 115 encircling the ported portion of said cylindrical shell whereby the exhaust air is caused to encircle the shell before being discharged into atmosphere.

4. In a grinder of the character described, 120 a cylindrical shell having a segmental portion cut away, eccentrically bored bearing housings spaced apart longitudinally in the shell against movement, a cylindrical block provided at one end with a trunnion and at the other end with a spindle, the trunnion being mounted in one of said bearing housings while the spindle is journaled in the other bearing housings for holding said block eccentrically in said shell in close relation with 125 130

one side of the shell, said cylindrical block having radial slots extending lengthwise thereof, blade members loosely slideable in said slots, thrust collars arranged in said bearing housings at each end of the cylindrical block so as to rotate with the latter and constitute closures for the ends of the radial slots, one of said bearing housings having an air duct disposed lengthwise thereof, the cylindrical shell being provided with exhaust ports at a point removed from the point of contact between the shell and cylindrical block, an air controlling valve rotatably secured to one end of the shell, a valve housing secured to the end of the shell about said valve against rotation and provided with ports adapted to register with the ports of said valve, a controlling handle for rotating said valve.
